[57]

CLAIM

The ornamental design for a toy gas pump, substantially as shown and described.

DESCRIPTION

FIG. 1 is a front perspective view of a toy gas pump showing my new design;

FIG. 2 is a bottom plan view thereof;

FIG. 3 is a right-side elevational view thereof;

FIG. 4 is a left-side elevational view thereof; and

FIG. 5 is a rear elevational view thereof.

Portions of the tube members have been shown in fragment in FIGS. 2 through 5 for ease of illustration.

FIG. 1

FIG. 2

FIG. 3

FIG. 4

FIG. 5
